Design No. 12,093, dated January 4, 1881.

UNITED STATES PATENT OFFICE.

H. CLAY BASCOM AND CYRUS A. HODGES, OF TROY, ASSIGNORS TO RUSSELL WHEELER, SON & CO., OF UTICA, NEW YORK.

DESIGN FOR A STOVE.

SPECIFICATION forming part of Design No. 12,093, dated January 4, 1881.

Application filed November 24, 1880. Term of patent 3½ years.

To all whom it may concern:

Be it known that we, H. CLAY BASCOM and CYRUS A. HODGES, each of the city of Troy, in the county of Rensselaer and State of New York, have jointly invented and produced a new and original ornamental Design for Stoves, of which the following is a specification, reference being had to the accompanying cut, print, or engraving of a stove which embodies our said new design.

The design for the legs consists, essentially, of the band-like top part, A, having ovolos-shaped ends b, ground e, and row of radial ornaments d, in combination with the main portion B, having the ornamental edge-moldings e, swelling surface f, and main quadrilateral ornament g, having ornamental edges, and the four sub-ornaments g', all shaped and arranged together so as to present the appearance represented in the accompanying print.

The design for the door-frames consists of the ornamental arch D, composed of the surface h, the top border-molding, i, of curved and angular shape in the direction of its length, the branching middle ornament, j, and corner ornaments k, and the lower border-molding, composed of the four subarches l, united by the pendent ornaments m and upright ornaments m', all shaped and arranged together as represented in the accompanying engraving.

The design for the end door consists of the upper and larger section, E, and smaller projecting section F, said upper section having the central compound quadrilateral ornament, n, with the ornamental projections n' at the sides, top, and bottom, the panel-surface o, the compound ornamental inner border, p p', and the compound corner ornaments p'', and the said lower section having the central oblong tablet, q, panel-surface q', corner ornaments q'', and ornamental border q''', all shaped and arranged substantially as shown in the accompanying cut.

The design for the side door consists of the upper section, G, having therein the four damper-apertures r, of uprightly-oblong form, with straight bottoms and sides and round arched tops, in combination with the projecting lower section, H, having the two illumination-apertures s, with arched tops and straight sides and bottoms, and the one intervening and two

lateral compound ornaments, s', all shaped and disposed together as represented in the aforesaid engraving.

The design for the upper front ornament, I, 55 is composed of the oblong rectangular tablet, having the central projecting scroll-ornamented circular arcs, u, at the top and bottom, the scroll-ornaments u' projecting at the ends, and the ornamental letters u'', all shaped and arranged together so as to appear as represented in the aforesaid print.

The design for the cover J is composed of the outer compound border-molding, v, the series of alternately-different upwardly-pointed 65 ornaments w w', the series of scroll-ornaments x and scallop-border x' on the convexly-curved surface x'', and the compound ornament y on the vertically-concave surface z, all shaped and arranged together as shown in the aforesaid cut.

What we claim as our joint invention is—

1. The design for the legs, composed of the parts A b c d and B e f g g', all shaped and arranged together, as set forth. 75

2. The design for the door-frames, consisting of the parts D h i j k l m m', all shaped and combined as set forth.

3. The design for the end door, composed of the section E, having the parts n n' o p p' 80 p'', and the section F, having the parts q q' q'' q''', all shaped and arranged together as set forth.

4. The design for the side door, composed of the section G, having the four parts r, and 85 the section H, having the two parts s, and three parts s', all shaped and combined as shown and described.

5. The design for the upper front ornament, I, composed of the parts t u u' u'', all shaped 90 and arranged together as set forth.

6. The design for the cover J, composed of the parts v, w w', x x' x'', and y z, all shaped and disposed together as set forth.

In testimony whereof we have hereunto set 95 our hands, in the presence of two subscribing witnesses, this 9th day of November, 1880.

H. CLAY BASCOM.
CYRUS A. HODGES.

Witnesses:

JAMES A. GILMAN,
CHESTER BASCOM.
